UNITED STATES PATENT OFFICE.

JAMES W. SIKES, OF PLYMOUTH, NORTH CAROLINA.

CAP OR WITHE FOR THE MASTS OF VESSELS.

Specification of Letters Patent No. 11,461, dated August 1, 1854.

To all whom it may concern:

Be it known that I, J. W. SIKES, of Plymouth, in the county of Washington and State of North Carolina, have invented certain new and useful Improvements in the Construction of Withes for the Tops of the Fore and Main Masts of Fore-and-Aft Vessels; and I do hereby declare the following to be a full, clear, and exact description of the same, and of the method heretofore practiced in making and using the same, reference being had to the accompanying drawings, making a part thereof, in which—

Figure 1, represents the method now practiced of making and using the withes, and Fig. 2 represents my improved plan.

To enable others skilled in the art to make and use my invention, I will proceed to describe the same with reference to the drawings.

In Fig. 1, A represents a fore or main mast, and B, a top mast, passing through a ring or eye in the upper with C, which is placed over the top of the mast A. The top mast may be stepped into the crosstrees in any of the well known ways. a is an eye in the with C, to which the spring-stay, or top-man lift block D, is hooked, over which the stay E, passes. Underneath the top with C, and about a foot therefrom is another with F, to an eye b, in which is hooked the peak-block G. In both these withes C, F, the eyes have been wrought in the solid metal, and whenever said eyes become worn, even to the extent of making them liable to give way, the whole with must be removed, which is both troublesome and expensive particularly at sea.

Now the nature of my invention consists in so constructing a single with, as to serve all the purposes, of the two as heretofore described, and in so connecting with it, all the parts liable to be worn by chafing, as that they can be removed and replaced without disturbing the with on the mast head, and thus by carrying spare stock in the vessel to be able to meet any emergency in connection with this part of the vessel's rigging.

Fig. 2, represents a perspective view of my improved with, turned on its side so as to represent all its parts. H, is the part fitting over the mast head and I, the hole through which the top-mast passes. J, is a main bar properly secured to the jaws c c of the with by screw bolts d, d. The main bar J, is of an L form, being secured at its angle to the with, and it is provided at the ends of each of its arms with shackles K, K', to the former of which (K) the spring stay or foreman lift block may be hooked, and to the other one (K'), the peak block, and thus avoid the necessity of two withes, as in Fig. 1. The shackles, are put on by screw bolts e, and when they become worn or chafed, may be removed and replaced without disturbing the with on the mast. The screw bolts should have eyes in their heads instead of nicks, so that with a marlin spike, they may be removed and replaced at any time.

It frequently happens that in a single voyage, the eye of the with, if not chafed through, is so worn as to make it unreliable, and as a matter of caution, unfit for use, and by constructing the shackles, main bar and with after my plan, by having spare stock aboard, any portion may be removed and replaced by others at sea or in port.

Having thus fully described the nature of my invention, and shown wherein it differs from what has heretofore been done, what I claim therein as new and desire to secure by Letters Patent, is—

The construction of a with with a main bar and shackles substantially as described, so that one with will serve all the purpose of the two heretofore used, and so that all its wearing or chafing parts may be removed and replaced by others without disturbing it on the mast, as set forth.

J. W. SIKES.
